FIG. 12

FIG. 14

FIG. 13

FIG. 1 is a front view of a set of chessmen showing the design, and wherein from left to right are shown the king, queen, bishop, knight, rook and pawn.

FIGS. 2, 3, and 4 are top, right side and bottom views, respectively, of the king of the set of chessmen.

FIGS. 5, 6, 7, and 8 are right side, left side, top and bottom views, respectively, of the queen of the set of chessmen.

FIGS. 9, 10, and 11 are right side, top and bottom views, respectively, of the bishop of the set of chessmen.

FIGS. 12, 13 and 14 are left side, rear and bottom views, respectively, of the knight of the set of chessmen.

FIGS. 15, 16, and 17 are right side, top and bottom views, respectively, of the rook of the set of chessmen.

FIGS. 18, 19 and 20 are top, right side and bottom views, respectively of the pawn of the set of chessmen.

I claim:

The ornamental design for a set of chessmen, as shown.
